UNITED STATES PATENT OFFICE.

EDWARD S. STIMPSON, OF HOPEDALE, MASSACHUSETTS, ASSIGNOR TO THE DRAPER COMPANY, OF SAME PLACE AND PORTLAND, MAINE.

LOOM-TEMPLE.

SPECIFICATION forming part of Letters Patent No. 668,133, dated February 12, 1901.

Application filed June 23, 1900. Serial No. 21,265. (No model.)

To all whom it may concern:

Be it known that I, EDWARD S. STIMPSON, a citizen of the United States, and a resident of Hopedale, in the county of Worcester and State of Massachusetts, have invented an Improvement in Loom-Temples, of which the following description, in connection with the accompanying drawings, is a specification, like characters on the drawings representing like parts.

This invention relates to loom-temples; and it has for its object the production of a novel construction and arrangement of parts, the temple being provided with thread-parting means by which the filling-thread is engaged with greater facility and accuracy, the weight of the thread itself assisting in holding it in place during the operation of the parting means.

The various novel features of my invention will be hereinafter described, and particularly pointed out in the following claims.

Figure 1 is a cross-sectional view of the breast-beam and part of the lay of a loom with one embodiment of my invention applied thereto, the temple being shown in normal condition. Fig. 2 is a side elevation, enlarged, of the temple shown in Fig. 1; and Fig. 3 is a top or plan view thereof.

My invention, so far as the thread-parting means is concerned, is particularly adapted for use with looms wherein the filling is replenished automatically to sever the end of a fresh supply of filling between the selvage of the cloth and the hopper or battery which contains the supplies of fresh filling.

The loom-frame A^X, lay A³, breast-beam A⁴⁰, having the temple-stand A, and the temple shank or bar B, adapted to slide in the stand, may be and are of usual construction, the temple being moved back or toward the lay by the usual spring S. (See dotted lines, Fig. 3.)

The pod B' is slotted at a to receive an upward steel blade a', which is secured at its upper end, as at 20, Fig. 2, in the cap B², substantially as in United States Patent No. 585,465, dated June 29, 1897, and in the slot in the pod I have herein shown a bar c, bifur-

cated at its inner end to straddle the blade a', as at c², the bifurcated end being formed as an upturned hook c³, which normally projects beyond the face of the pod and cap, as shown. The outer end of the bar has a laterally-extended shoe 6, which slides and rocks on the extension or ear b of the pod, the slot extending through the ear. An upturned heel c⁴ is secured to or forms a part of the bar c at the end adjacent the shoe, the heel being shouldered at 4 to slide on the top of the temple-shank B, between an abutment b³ thereon and a lug or stop b⁴, also on the shank. The heel c⁴ is normally maintained in the position shown by a spring s^X, coiled around a stud b' on the ear b and having its free end in engagement with a stud c⁵ on the upturned part c⁶ of the bar c, the other end of the spring bearing against a shoulder 10 of the pod, Figs. 1 and 3.

It will be noted by reference to Fig. 1 that the heel c⁴ is located above the temple as a whole, and I have provided an actuator to engage and operate the temple and thread-parting means, the actuator being shown as a bunter or projection a¹⁰, Fig. 1, mounted on the lay above the shuttle-race—as, for instance, on the reed-cap R. When the lay beats up, the hook c³ is brought into position beneath the filling-thread extended from the selvage toward the loom side, and the said thread is caught and held by the upturned hook. As the lay continues its forward movement the actuator a¹⁰ engages the heel c⁴ and moves it forward (to the left in the drawings) against the action of the spring s^X, so that the hook c³ draws the thread across the blade a', and the thread is parted. The heel c⁴ is brought into engagement with the abutment b³ on the temple-shank after such operation of the parting means, and as the lay completes its forward movement the temple is moved thereby toward the breast-beam or forward.

By effecting the operation of the parting means first the desired parting of the thread is insured, and the forward movement of the temple cannot take place first, inasmuch as such movement of the temple is effected by

or through the actuation of the parting means. This arrangement prevents the operation of the parting means too tardily or not at all, as has sometimes been the case in former devices of this general character.

By locating the heel, as herein shown, above the temple rather than below it the different parts are in plain view, so that errors of adjustment can be readily seen and corrected and the blow of the actuator on the lay is brought nearer the line of movement of the temple-shank.

As in United States Patent No. 585,465, the bar *c* first rocks on the ear *b* and then slides, the rocking lifting the hook slightly before drawing it toward the blade *a'*. The spring *s*^x gives a yielding movement to the heel *c*⁴ when it is actuated, so that it is not brought up with a heavy shock against the abutment *b*³ on the temple-shank.

Having described my invention, what I claim as new, and desire to secure by Letters Patent, is—

1. A temple having a shank, a stand in which it slides, a fixed abutment on the upper side of the shank, and an adjacent, yieldingly-controlled heel adapted when moved in one direction to engage the abutment and slide the shank inward.

2. A temple, a stand in which it is mounted to slide, thread-parting means carried by the temple, a movable member of said means having an upturned heel, and means to engage the

heel to successively operate the thread-parting means and slide the temple in its stand. 35

3. A reciprocating temple having an abutment, a blade, an upturned hook coöperating therewith and slidable on the temple, an upturned heel movable with the hook and adapted to engage the abutment and move the temple forward, and a spring to maintain the hook normally inoperative. 40

4. A temple provided with an upright blade, combined with a slide-bar having an upturned hook to coöperate with the blade, a shoe to 45 slide on the temple, and an upturned heel by which the slide-bar is actuated.

5. A reciprocating temple having a fixed, and a spring-controlled movable thread-parting member, mounted upon it, the movable member having an upturned hook to receive the thread, an upturned heel on said member, extended above the temple, means to limit the movement of the heel relatively to the temple, and an actuator to engage and 50 effect limited movement of the heel relatively to the temple, continued movement of the heel moving the temple in unison therewith.

In testimony whereof I have signed my name to this specification in the presence of 60 two subscribing witnesses.

EDWARD S. STIMPSON.
